EVAPORATOR

Bernard C. Johnson, Libertyville, Ill., assignor to
Houdaille-Hershey Corporation, Detroit, Mich.,
a corporation of Michigan

Application December 2, 1940, Serial No. 368,187

8 Claims. (Cl. 62—126)

This invention relates to sheet metal heat exchangers.

More specifically the invention relates to U-shaped sheet metal evaporator units for refrigerators which units have shelves carried by the side walls thereof and equipped with refrigerant circulating ducts for cooling articles mounted thereon.

This application is a continuation in part of my copending application entitled: "Evaporator," Serial No. 279,878, filed June 19, 1939, now Patent No. 2,310,906, February 9, 1943.

In the copending application above referred to there is disclosed and claimed a U-shaped sheet metal evaporator unit formed by securing two embossed flat sheets of metal together and bending the embossed sheets into the shape of a U to provide the side walls and bottom of a sharp freezing chamber. The outer sheet of the unit is embossed with a pair of header depressions extending across each end portion thereof. Embossed refrigerant passageways extend longitudinally of the sheet and communicate with the header depressions. A transverse inlet passageway is embossed intermediate the ends of the longitudinal passageways in intersecting relation therewith. This transverse inlet passageway serves as a manifold to distribute refrigerant to each of the circulating passageways.

The outer sheet is also embossed with an outlet passageway communicating with the outer header depression and extending throughout the length of the sheet so that both of the top headers can be exhausted through this single passageway.

The inner sheet is also provided with header depressions for complementary registration with the header depressions in the outer sheet. The two sheets, when secured together, form tubular header chambers in spaced superimposed relation on each leg of the U-shaped unit. In the said application these header chambers are connected through embossed ducts formed on the outer sheet.

The present invention now relates to improvements in evaporator constructions such as are disclosed in said application Serial No. 279,878. These improvements deal with the formation of embossed flutes on the inner sheet of the unit for connecting the superimposed headers where-

by natural baffles are provided to prevent the splashing of unspent liquid refrigerant into the upper header chambers.

An important feature of the present invention 5 is the provision of one or more refrigerated shelves for the evaporator unit, which shelves have substantially no contact with the walls of the unit in order that metal coating material such as zinc can readily flow between the shelves and the unit walls, thereby eliminating a heretofore-required soft soldering operation.

Another feature of this invention includes the provision of upstanding legs on the refrigerant inlet and outlet tubes, which legs serve as tray 15 stops.

It is, then, an object of this invention to provide sheet metal evaporator units with a superimposed pair of headers connected through embossed flutes in offset relation to the embossed refrigerant flutes of the unit.

Another object of the invention is to provide a sheet metal evaporator unit having a separate shelf fixedly mounted therein in spaced relation from the walls thereof to facilitate flowing of 20 coating material between the evaporator unit and shelf.

A specific object of the invention is to provide an improved connection between the shelf and walls of sheet metal evaporator units.

Another specific object of the invention is to provide upstanding legs on the inlet and exhaust tubes connected to an evaporator unit whereby said legs can serve as tray stops.

A further object of the invention is to provide a sheet metal evaporator unit with a refrigerated shelf maintained in spaced relation from the walls of the unit except at minute contact areas to thereby eliminate the necessity for soldering or welding the shelf to the evaporator walls.

Other and further objects of the invention will be apparent to those skilled in the art from the following detailed description of the annexed sheets of drawings which disclose preferred embodiments of the invention.

On the drawings:

Figure 1 is a top plan view of a sheet metal evaporator unit with a refrigerated shelf according to this invention.

Figure 2 is a side elevational view of the evaporator unit shown in Figure 1.

Figure 3 is a rear end elevational view of the evaporator unit shown in Figures 1 and 2.

Figure 4 is an enlarged broken horizontal cross sectional view taken along the line IV—IV of Figure 3.

Figure 5 is a further enlarged cross-sectional detail view illustrating the manner in which coating material can readily flow between the shelves and side walls of an evaporator unit according to this invention.

Figure 6 is an enlarged vertical cross-sectional view taken along the line VI—VI of Figure 2.

Figure 7 is an enlarged fragmentary horizontal view taken along the line VII—VII of Figure 2.

Figure 8 is a rear end elevational view of an evaporator unit according to this invention having two superimposed refrigerated shelves.

Figure 9 is a vertical cross-sectional view taken along the line IX—IX of Figure 8.

Figure 10 is a fragmentary cross-sectional view along the line X—X of Figure 9.

As shown on the drawings:

In Figures 1 to 3 inclusive the reference numeral 10 designates generally an evaporator unit composed of an inner metal sheet 11 and an outer metal sheet 12. The sheets 11 and 12 are secured together by brazing, spot-welding, stitch-welding or the like. The evaporator unit 10 is U-shaped, as best shown in Figure 3, to define spaced vertical side walls 13 and a bottom 14 of a sharp freezing chamber 15.

The top ends of the side walls 13 can be bent horizontally inward to provide flanges 16 which may be apertured as at 17 (Fig. 1) for receiving suspension means to hang the unit in a refrigerator cabinet, preferably from the top wall of the cabinet.

The outer sheet 12 has semi-cylindrical flutes 18 and 19 embossed therein near the upper end thereof as shown in Figures 2 and 3. The inner sheet 11 has complementary semicylindrical embossed flutes 18a and 19a forming, with the flutes on the outer sheet, a pair of superimposed header chambers 20 and 21 on each side wall 13 of the unit at the upper ends of the side walls.

The outer sheet 12, as shown in Figures 2 and 3, has embossed flutes 22 extending around the unit and communicating with the lower headers 21.

A transverse flute 23 is embossed in the outer sheet 12 and extends longitudinally along the bottom 14 of the unit in communication with each of the flutes 22. Refrigerant is introduced into the flute 23, flows therefrom through the refrigerant distributing passageways provided by the flutes 22 around the bottom and side walls of the unit into the lower header chambers 21.

As best shown in Figures 2, 3, 6, and 7, the inner sheet 11 is further embossed as at 24 and 25 on each side wall 13 thereof to provide passageways connecting the header chambers 20 and 21 on each side wall.

As best shown in Figure 6, refrigerant R entering the lower header chamber such as 21 from the distributing flutes 22 may assume the indicated level. As refrigerant gases pass through the liquid refrigerant from the distributing ducts 22 slugs S of liquid or unspent refrigerant will be thrown against the upper portion of the embossed depression 19 on the outer sheet and cannot pass directly through the passageway provided by the embossed duct 24 to the upper header chamber 20. As a result, the offset relation-

ship between the passageways 22 and 24 as well as between the passageways 22 and 25 hinders the flow of unspent refrigerant to the top header chambers 20 while the gasified or spent refrigerant can freely pass into the upper header.

The gasified or spent refrigerant is removed from the upper header chamber 20 through an embossed flute 26 on the outer sheet 12. The flute 26 extends around the side and bottom walls of the unit and communicates with a flute 27 embossed on the inner sheet 11 as shown in Figures 3 and 10. The outlet passageway provided by the flute 26 communicates with the rear ends of the top header chambers as shown in Figure 2.

A shelf 30 composed of a flat top plate 31 and a bottom plate 32 brazed or welded to the plate 31 and embossed as at 33 to provide a serpentine refrigerant passageway throughout the shelf area, is secured to the side walls 13 of the unit in a manner so as to have minimum contact with the unit. The shelf 30 thus has the longitudinal sides thereof turned down to provide vertical flanges 34 spaced inwardly from the sheet 11 of the unit. Each flange has two small localized outwardly embossed protuberances 35 which slope into substantially point contact with the inner sheet 11. A rivet 36 passes through each protuberance 35 and through the side walls 13 of the unit for fixedly securing the shelf to the side walls. As a result a space 37 is provided between the side walls 13 and the shelf, and the shelves only contact the side walls at the rim edges of the protuberances 35.

It is customary to coat the evaporator unit after the same has been fabricated for protecting the sheet metal. If the evaporator unit is made from sheet steel it is desirable to zinc dip the entire unit thus forming a zinc coating thereon. Heretofore the evaporator shelf always had an extensive area contact with the walls of the unit and the coating material could not strike down between the contacting areas. As a result it was necessary to soft solder around the peripheral portions of each contacting area for sealing off the contacting area. These soldering operations were time-consuming and expensive.

In accordance with this invention, as shown in Figure 5, however, the space 37 between the shelf and the evaporator unit now makes it possible for a zinc coating 38 to flow between the shelf and side walls of the unit and form its own protecting fillet 38a around any minute contacting area between the shelf and unit.

The rear end of the shelf 30 has an upstanding tube 40 soldered thereon in communication with one end of the embossed flute 33. Refrigerant is introduced through this tube 40, flows through the embossed flute 33 to another upstanding tube 41 which is soldered to the shelf 35 at the other end of the flute 33. The tubes 40 and 41 preferably have vertical upstanding legs and rearwardly extending legs. The rearwardly extending leg of the tube 40 can receive the compressed and condensed refrigerant while the rearwardly extending leg of the tube 41 receives a tube 42 extending downwardly at the rear side of the unit to the inlet flute 23. The refrigerant first flows through the shelf duct 33 and thence around the rear end of the unit into the inlet duct 23 where it is distributed to the circulating passageways provided by the flutes 22.

The embossed flute 27 on the bottom 14 of

the unit receives an upstanding outlet tube 43 at the central portion thereof. As shown in Figure 2, the tube 43 extends vertically upward and then slopes out beyond the rear end of the unit.

The inlet tube 40 and the outlet tube 43 have their free ends closed by means of caps 44 to prevent entrance of foreign material into the passageways of the unit. These caps are of course removed when the unit is installed in a 10 refrigerating system.

The upstanding legs of the tubes 40 and 41 provide stops for ice trays T mounted on the shelf 30 as shown in dotted lines in Figure 2. Likewise the embossed flute 27 and the vertically upstanding portion of the tube 43 forms a stop for ice trays such as T mounted on the bottom of the unit.

In the modification shown in Figures 8 and 9, the evaporator unit 10a is constructed the same 20 as the evaporator 10 but has higher side walls 13a than the evaporator 10. The same type of refrigerant distributing ducts, headers and connecting conduits are used. Two shelves 30a and 30b are provided bridging the space between the 25 side walls 13a in spaced superimposed relation. The shelves 30a and 30b have downturned side flanges 34a and 34b respectively secured to the side walls 13a of the unit in the same manner as the flanges 34 are secured to the side walls of the unit by means of the rivets 36. The downturned collars 35a and 35b hold the flanges in spaced relation from the side walls.

The shelves 30a and 30b have serpentine refrigerant passageways 33a and 33b provided 35 therein. An L-shaped inlet pipe 40a has the vertical leg thereof soldered to the shelf 30a communicating with the passageway 33a. Refrigerant is introduced through the tube 40a and flows through the passageway 33a to a second L-shaped tube 41a having the vertical leg communicating with the other end of the passageway 33a and having the horizontal leg thereof receiving a connecting tube 42a. The connecting tube 42a extends around the rear 40 end of the shelf 30a to the horizontal leg of a second L-shaped tube 41b. The vertical leg of the tube 41b is soldered to the shelf 30b and communicates with the passageway 33b. A fourth L-shaped tube 40b is soldered to the shelf 30b at the outlet end of the passageway 33b and receives a tube 42b communicating with the inlet flute 23a of the unit. The suction tube or outlet tube 43 is the same as the outlet tube 43 for the unit 10 and is in communication with the outlet duct 21 of the unit.

It will be noted that the inlet manifold flute 23a is in offset relation from the central portion of the bottom of the unit 10a, whereas in the evaporator unit 10 the inlet flute 23 is at the 60 center of the bottom of the unit.

The refrigerant is introduced into the tube 40a, flows through the shelf passageway 33a, thence out of the tube 41a through the tube 42a into the tube 41b. From the tube 41b it flows through the passageway 33b of the lower shelf 30b and thence out of the tube 40b, through the connecting tube 42b and into the inlet manifold 23a.

Thus the refrigerant first flows through both shelves 30a and 30b before it reaches the unit ducts. The exhaust refrigerant is removed from the unit through the suction tube 43.

As shown in Figure 9 the upstanding portions

5 of the tubes 40a, 40b, and 43 serve as stops for ice trays T mounted on the top of the shelves 30a and 30b and on top of the bottom 14 of the unit.

From the above descriptions it should be understood that this invention now provides improvements in sheet metal evaporator units which have natural baffles for retarding flow of unspent refrigerant into the outlet passageway from the unit. The units of this invention also utilize upstanding refrigerant tubes on the shelves and bottoms for ice tray stops thereby avoiding heretofore-required additional parts.

An important feature of the units of this invention is the spacing of the shelves from the side walls of the unit so that heretofore-required soldering operations are eliminated and coating material will readily strike down between the shelves and walls of the units.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A sheet metal evaporator unit having a bottom and side walls with a pair of superimposed header chambers in each side wall, refrigerant circulating flutes on one face of the unit connecting the lower header chambers, flutes on the opposite face of the unit connecting the header chambers of each pair whereby the passageways defined by the refrigerant circulating flutes are in offset relation from the passageways defined by the flutes connecting the header chambers of each pair, a shelf bridging the side walls above the bottom of the unit, localized lateral projections spacing the shelf from the side walls, refrigerant circulating flutes on the shelf, a refrigerant inlet tube secured to said shelf and having an upstanding leg portion at the rear end of the shelf, a refrigerant outlet tube having an upturned leg portion secured on said shelf and joining the shelf flutes with the refrigerant circulating flutes of the unit, a suction flute embossed on the unit connecting the top chambers of said pairs, and a single suction tube communicating with said embossed flute and having a leg portion extending upwardly from the bottom of the unit at the rear end thereof, said upstanding leg portions of the tubes being arranged to act as tray stops.

2. A sheet-metal evaporator unit comprising a pair of secured-together contiguous metal sheets defining the side walls and bottom of a sharp freezing chamber, said sheets being embossed to define a pair of superimposed header chambers in each side wall, one of said sheets being further embossed to define refrigerant circulating ducts connecting the lower header chambers of said pairs, the other of said sheets being embossed to define passageways connecting the headers of each pair, said ducts and passageways being in offset relation to retard flow of unspent refrigerant into the top header chamber, a shelf bridging the side walls of the unit in spaced relation from the bottom thereof having localized laterally extending projections in restricted contact with the said side walls for holding the shelf in spaced relation from the unit, and refrigerant inlet and outlet tubes secured to said shelf having upstanding leg portions adapted to

serve as ice tray stops at the rear end of the shelf.

3. A sheet metal evaporator unit comprising a pair of secured-together contiguous metal sheets defining the side walls and bottom of a sharp freezing chamber, said sheets being embossed to define a pair of superimposed header chambers in each side wall, one of said sheets being further embossed to define a plurality of refrigerant circulating ducts connecting the lower header chambers of said pairs, the other of said sheets being embossed to define passageways connecting the upper and lower header chambers of each pair, a pair of secured-together contiguous metal sheets having flanges at the longitudinal sides thereof and together defining a shelf for the unit, one of said shelf defining sheets being embossed to form a refrigerant duct having the ends thereof adjacent the rear edge of the sheet, upstanding tubes secured to the top shelf defining sheet in communication with the ends of said duct, apertured protuberances projecting from said flanges, rivets extending through said protuberances securing the plates to the side walls of the unit in spaced relation from the bottom thereof, and a tube connecting one of said upstanding tubes with said refrigerant circulating ducts to place said one upstanding tube in fluid flow communication with said circulating ducts whereby refrigerant can be introduced into the other of said upstanding tubes for flowing through the duct in the shelf to the other of said upstanding tubes and thence through the connecting tube to the refrigerant circulating ducts and said upstanding tubes being arranged to serve as tray stops.

4. A sheet metal evaporator unit comprising a pair of secured-together contiguous metal sheets defining the side walls and bottom of a sharp freezing chamber, said sheets being embossed to define a pair of superimposed header chambers in each side wall, one of said sheets being further embossed to define refrigerant circulating ducts connecting the lower header chambers of said pairs, and the other of said sheets being embossed to define passageways connecting the top and bottom header chambers of each pair, said ducts and said passageways being in offset relation to retard flow of unspent refrigerant from the ducts to the top header chambers.

5. A heat absorber comprising sheet metal defining spaced opposed side walls, a shelf bridging said side walls having turned-down flanges in spaced parallel relation from the side walls, apertured laterally projecting embossed portions on said flanges in rim engagement only with said side walls, securing means extending through the side walls and through the apertures of the em-

bossed portions for uniting the shelf with the side walls, and coating material covering the side walls and flanges to protect the same against corrosion.

- 5 6. A sheet metal evaporator unit comprising a pair of secured-together contiguous metal sheets defining the side walls and bottom of a sharp freezing chamber, said sheets being embossed to define a pair of superimposed header chambers
10 in each side wall, one of said sheets being embossed to define a plurality of refrigerant circulating ducts connecting the lower header chambers of said pairs, at least one of said sheets being further embossed to define a passageway
15 joining the top header chambers of said pairs, a single exhaust tube communicating with said passageway, a shelf spanning the side walls of said unit in spaced relation from the bottom thereof, a refrigerant duct formed under said shelf, an inlet tube for supplying refrigerant to said duct, and an outlet tube connecting said duct with the refrigerant circulating ducts in said unit whereby a single inlet and a single outlet provide for the circulation of refrigerant
20 through the shelf and through the unit.
25 7. In an evaporator unit including a pair of secured-together contiguous metal sheets defining the side walls and bottom of a sharp freezing chamber, said sheets being embossed to define a header chamber in each side wall, the outer of
30 said sheets being further embossed to define a passageway connecting the header chamber in one side wall with the header chamber in the other side wall, the inner of said sheets being
35 embossed along the bottom of the unit to form a rib across the rear end of the unit adapted to act as a stop for articles mounted on the bottom of the unit and said rib defining a passage in communication with said passageway.
40 8. The method of protecting against corrosion of an evaporator unit of the type having a shelf spanning side walls of the unit and carried by said side walls which comprises forming flanges on the longitudinal side edges of the shelf in
45 spaced relation from the side walls of the evaporator unit, embossing localized laterally extending projections at materially spaced intervals along said flanges, bending said embossed portions into sloping rim edge engagement with the side walls to maintain the flanges in spaced relation from the side walls while contacting said side walls only at the rim edges of the embossed portions, securing the embossed portions to the side walls, and coating the assembly to cause
50 55 the coating material to strike down between the flanges and side walls of the unit.

BERNARD C. JOHNSON.
